UNITED STATES PATENT OFFICE.

EDWARD WESTON, OF NEWARK, NEW JERSEY, ASSIGNOR TO THE UNITED STATES ELECTRIC LIGHTING COMPANY, OF NEW YORK, N. Y.

ELECTRIC-LIGHTING SYSTEM.

SPECIFICATION forming part of Letters Patent No. 316,709, dated April 28, 1885.

Application filed November 28, 1884. (No model.)

To all whom it may concern:

Be it known that I, EDWARD WESTON, a subject of the Queen of Great Britain, and a resident of Newark, in the county of Essex and State of New Jersey, have invented certain new and useful Improvements in Electric-Lighting Systems, of which the following is a specification, reference being had to the drawings accompanying and forming a part of the same.

In certain patents granted to the United States Electric Lighting Company, as my assignees, September 9, 1884, Nos. 304,882, 304,883, and 304,884, I have shown and described a system of electric lighting in which incandescent lamps or other similar translating devices are run two or more in series in parallel or multiple circuits from two main conductors, and in which provision is made for preserving the continuity of each cross-circuit in case any number of lamps less than all in that circuit be extinguished, by substituting equivalent resistances for the lamps withdrawn, and also for interrupting the circuit through said resistances; or, in other words, breaking the cross-circuit when all the lamps in the same are withdrawn. In another form of multiple-series distribution the line at certain points is divided into a number of branches, and the lamps are included singly or in limited numbers in each branch. A considerable number of such groups of derived circuits may be formed in the same line, the groups being in series. To this particular form of circuit my present invention relates, the object being to replace extinguished lamps or other like devices of any group by equivalent resistances, so that the distribution of current in the branches or derived circuits may always be uniform, and also to provide a final cut-out for closing a circuit of low resistance around a group of derived circuits when all the lamps of such group have been extinguished.

In carrying out my invention I employ with each group of lamps a supplemental circuit containing an electro-magnetic circuit-controller, and having as many breaks as there are lamps in the group. The low-resistance shunt is interrupted so long as any lamps are

active, but is closed by the supplemental circuit through the instrumentality of the circuit-controller as soon as all the lamps are extinguished. In an application of even date herewith I have shown and described a system of this character in which the supplemental circuit contained a series of breaks open during the operation of the lamps, but closed by the mechanism that extinguished them or that is brought into operation by their extinguishment. My present application, however, is based on a different arrangement of the controlling-circuit, which is as follows: The breaks are in cross or multiple circuits between the positive and negative conductors of the controlling-circuit, so that the circuit is not actually broken unless all the breaks are open, but completed if any one of the breaks is closed. The switches that control the lamp-circuits also control the branches containing the breaks, the latter being closed by the switches when they close the lamp-circuits, and conversely. It follows from this arrangement that if any lamp is burning the controlling-circuit is complete through one of its branches, but that when all the lamps have been turned off the controlling-circuit is interrupted. By taking advantage of this I cause the interruption of the controlling-circuit to close the low-resistance shunt around the group of lamps, as will be hereinafter described.

The controlling-circuit may be either independent of the main or lighting circuit, in which case a battery is used to supply the necessary current, or it may be in derivation to the main circuit, in which case some auxiliary devices may be employed for insuring the proper action of the circuit-controller operated by it.

The details of the system may be described by reference to the accompanying drawings, in which—

Figure 1 is a diagram of the system, showing the use of an independent controlling-circuit; Fig. 2, a diagram of the same with a controlling-circuit in derivation to the main.

Let A designate the conductor of a main line; B B, a given number of divisions of such line brought into derivation or multiple are

and united to the main line by the conductors C C. In each branch or division B is included an electric incandescent lamp, D, or some similar translating device, this being a well-known modification of the plan or system for distributing current known as "multiple series." In each branch B is also an electromagnetic cut-out, E, and a break, F. Around each lamp and break is a resistance-circuit, G, containing a resistance-coil, R, equivalent to one lamp and connected with and controlled by the cut-out E, the purpose in this being to provide for the automatic substitution of the resistance for the lamp, whether the latter be extinguished by its switch or extinguished by the destruction of its carbon.

H H designate switches to be operated by hand for the purpose of interrupting the circuit through the lamps when so desired.

K K' are the positive and negative wires of the supplemental or controlling circuit, and k the branches or cross-circuits between the same.

In one of the main wires K K' is included an electro-magnet, L, and in each branch k is a break, M, in proximity to one of the breaks in the lamp-circuits, so that both are controlled by the same switch.

The switches H are provided with double contacts and so arranged with reference to the breaks in the lamp-circuits and the corresponding breaks in the controlling-circuit as to close or open both by the same movement.

In Fig. 1 a small battery, N, is shown in the controlling-circuit K. The electro-magnet L is provided with a pivoted armature-lever, l, that forms the contact-lever of a switch in the shunt-circuit O around the entire group of derived circuits and all the devices included therein. If one or more of the lamps are active the circuit K is closed through one or more of its branches and the magnet J energized. The armature-lever l will therefore be drawn away from its stop and the circuit O interrupted. The circuit K is broken only when all the lamps are out and all its branches interrupted, in which event the entire line-current passes through the shunt O. The insertion of a single lamp evidently breaks the shunt O, directing the current through the active lamp and the resistance-coils of the remaining lamps.

In Fig. 2 the circuit K is derived from the main line and contains no battery; but its arrangement in other respects is the same as that described. In this case I have shown as a means of preventing the possible vibration of the contact-lever of the electro-magnet the following: A spring-impelled contact-lever, m, and a pivoted armature-lever, n, with a catch, n', that engages with the lever m and holds it out of contact with its stop. While the magnet is energized the armature-lever is held in engagement with the lever m; but when the circuit K is broken the spring S retracts the armature and sets

the lever m free, thus completing circuit O. This or some equivalent arrangement is desirable in this case, for the reason the relative resistances of the circuits O and K are such that when both are closed the amount of current that flows through the latter is extremely small. When one or more lamps are to be again connected with the circuit, the circuit O is broken and the levers set by hand.

In carrying out my invention I may use a great variety of mechanical devices operating on the general principle herein described. The control of the circuit K may, for example, be effected not only by the manual switches, but by the automatic switches or cut-outs, as will be readily seen by reference to the patents above mentioned, and in other respects the system may be modified within the limits of my invention.

In practice a number of the groups of derived circuits described are formed in series in the circuit A, and some means used to regulate the current generated, so that a uniform flow of current will be maintained.

It is possible to run more than one lamp in each branch by duplicating the devices described, and by making such other obvious changes as the circumstances of the case require.

What I claim is—

1. In a system of electrical distribution, in which a main line is divided at intervals into a group or given number of branches, the combination, with each branch in a group, of an electric lamp, a switch and a resistance arranged to be substituted for the lamp, and with each group of branches, of a shunt of low resistance around the same, a supplemental controlling-circuit having multiple or cross connections between its positive and negative wires, each containing a break controlled by a lamp-switch, a circuit-closer in the shunt-circuit, and an electro-magnet in the supplemental controlling-circuit for operating the same, as set forth.

2. In a system of electrical distribution, in which a main line is divided at intervals into a group of a given number of branches, the combination, with each branch in a group, of an electric lamp, a manual switch, an automatic switch or cut-out, and a resistance for replacing the lamp, and with each group of branches, of a shunt of low resistance, a supplemental controlling-circuit having multiple or cross connections between its positive and negative wires, each containing a break controlled by a lamp-switch, a circuit-closer in the shunt-circuit, and a magnet in the supplemental controlling-circuit for operating the same, as and for the purpose described.

3. In a system of electrical distribution, in which a main line is divided at intervals into a group or given number of branches, the combination, with each branch in a group, of an electric lamp, a switch and a resistance to take the place of the lamp, and with each

group of branches, of a shunt-circuit of low resistance, a controlling-circuit derived from the main, and containing breaks that are controlled by the lamp-switches, an electro-magnet in the controlling-circuit, and a circuit-closer in the shunt-circuit operated thereby, as and for the purpose set forth.

In testimony whereof I have hereunto set my hand this 25th day of November, 1884.

EDWARD WESTON.
